UNITED STATES PATENT OFFICE

150,381

DESIGN FOR A MERRY-GO-ROUND

Randolph Stone, Chicago, Ill.

Application March 20, 1947, Serial No. 137,766

Term of patent 14 years

(Cl. D34—15)

To all whom it may concern:

Be it known that I, Randolph Stone, a citizen of the United States, residing at Chicago, in the county of Cook and State of Illinois, have invented a new, original, and ornamental Design for Merry-Go-Round, of which the following is a specification, reference being had to the accompanying drawings, forming a part thereof.

In the drawings:

Fig. 1 is a perspective of a merry-go-round, showing my new design.

Figs. 2, 3, 4 and 5 are details of the figures on the seat supporting bars, respectively.

The side of the merry-go-round not shown is substantially the same as the side thereof which is shown in Fig. 1.

I claim:

The ornamental design for a merry-go-round, substantially as shown and described.

RANDOLPH STONE.
